ELECTRIC RAZOR

Alfred J. Stecker, St. Petersburg, Fla., assignor of
one-half to Edwin L. Stecker, Detroit, Mich.

Application October 14, 1938, Serial No. 234,923

7 Claims. (Cl. 30—45)

This invention relates, in general, to razors and, in particular, to improvements in razors of the self-reciprocating type.

One of the objects of this invention is to provide a new and improved razor which is efficient, easy and safe to operate, readily assembled or disassembled, adjustable for permitting the operator to select and control the desired closeness of a shave, and economical in manufacture and use.

Another object is to provide a new and improved self-reciprocating razor with a blade which is operable for direct contact with the user's face and reciprocably movable in a path normal to the path taken by the razor proper, both the head and the blade of the razor being novelly constructed and said blade being novelly supported on said head.

Another object is to improve an electrically driven razor so as to render same substantially noiseless in operation, so as to provide a flexible connection between the driving and driven portions thereof, and so as to permit ready, thorough and safe cleaning of the parts requiring same.

Other objects and advantages of the invention will become readily apparent from a reference to the following specification taken in conjunction with the accompanying drawings, of which there are two (2) sheets and wherein:

Figure 1 is a longitudinal, horizontal sectional view through the new and improved electric razor;

Fig. 2 is a longitudinal, vertical sectional view through the razor shown in Fig. 1;

Fig. 3 is an elevational view looking toward the head end of the razor in Fig. 2;

Fig. 4 is a sectional view taken along the lines 4—4 in Fig. 2;

Fig. 5 is a front elevational view of the stationary table unit and the roller attached thereto, the clamp for the blade being shown in tilted, inoperative position;

Fig. 6 is a detailed front elevational view of the floating blade support;

Fig. 7 is a top view of the showing in Fig. 6, shown partly in section to illustrate details of its construction and securing means;

Fig. 8 is a partial view, in perspective, of the floating blade support of Figs. 6 and 7;

Fig. 9 is an elevational view of the blade;

Fig. 10 is a sectional view taken along the lines 10—10 in Fig. 2;

Fig. 11 is an elevational view of the razor showing a modified form thereof whereby the

head may be readily detached from or assembled to the casing;

Figs. 12 and 13 are views showing a modified form of blade support.

5 In Figs. 1 and 2 there is shown, generally at 10, an electric razor, the vibratory mechanism of and for which razor being enclosed within a casing 12. Casing 12 is hollow and of sturdy and non-conductive material, such as hard rubber, Bakelite, or the like, and has formed at one of its ends a lead inlet portion 14 and at the other of its ends a neck portion 16, the periphery of the latter at opposite sides thereof being formed to provide a pair of laterally extending flanges 18.

15 Except for the openings into casing 12 provided by the lead inlet and neck portions 14 and 16, respectively, said casing is sealed against entrance thereto of air and moisture from without.

Within and to the casing 12 between the lead inlet and neck portions 14 and 16, respectively, there is rigidly supported, such as by bolts or rivets 20, a pair of longitudinally spaced lugs 22 and 24. An inverted T-shaped bracket 26 is rigidly mounted at one side thereof to lug 22 by means of a pair of bolts 28, and an L-shaped bracket 30 is rigidly mounted at one side thereof to lug 24 by means of another pair of similar bolts 28. Supported onto and between brackets 26 and 30 and also by the two pairs of bolts 28 is

25 a U-shaped magnet 32 of any suitable design and construction and affording the necessary magnetic force in the vibratory mechanism of the razor 10. Between the ends of and about the magnet 32 is supported in the ordinary manner a magnetic coil 34 of any suitable design and construction and affording the required magnetic field in the actuation of the vibratory mechanism. Also confined within the casing 12, and having its laminations extending laterally of and

30 in parallelism with the magnet 32 and coil 34, is an armature 36 operable for rendering to the cutting unit of the razor the intended vibrations thereof.

35 One end of armature 36 is transversely flanged, as at 38, to provide a bearing portion 40 thereat, said bearing portion being rotatively supported upon the side of bracket 26 opposite the side supporting the magnet 32 and about a pivot pin or post 42 stationarily mounted in said side of said bracket. Arranged between the pin or post 42

40 and the bearing wall of the bearing portion 40 is an annular, flexible, resilient, insulating bushing or bearing 44, said bearing 44 being bonded, cemented or otherwise secured to said post and 45 said wall to eliminate noise and the necessity for

lubrication thereat. Pin or post 42 and bearing portion 40 are further insulated from each other by means of spaced insulating washers 46, the lower of said washers spacing said bearing portion from the supporting side of the bracket 26, and the upper of said washers spacing said bearing portion from a washer 48 which is employed for engagement with the latter by a transverse stop pin 50 in said pin or post 42 for preventing vertical displacement of the armature 36 from its support 26—42.

Still considering the pivoted end 38—40 of the armature 36, which armature is free to oscillate about the axis of the pin or post 42 except for the resilient opposition thereto caused by the insulating bearing or bushing 44, a driving arm 52 is rigidly connected at one of its ends to the forward end of the bearing portion 40 of the armature 36 and extends forwardly therefrom to a point just rearwardly of the flanged periphery of the neck portion 16 of the casing 12. About the free end of arm 52 is fixedly mounted an annular retaining member 54 wherein is disposed and to which is bonded, cemented or otherwise secured an annular, flexible, insulating coupling 56. Coupling 56 in turn receives in free engagement therewith one end of a driving pin 58, the other end thereof extending outwardly of the neck portion 16 of casing 12. It will be seen that the connection between the pin 58 and the arm 52, like the connection between the armature 36 and post 42, is insulated and is flexible and, therefore, noiseless, substantially universal and necessitous of no lubrication. In tight fitting engagement with and about the arm 52, and preferably sealed in any appropriate manner, such as by bonding or cementing, to the rear of the neck portion 16 of and within the casing 12, is a diaphragm 60 which is operable for permitting free movement of said arm yet sealing said casing against entrance of moisture thereinto through said neck portion.

The free or rear end of armature 36 terminates at a position within the casing 12 between a pair of spaced, flexible, insulated stops 62 and 64, stop 62 being adjustably mounted in a transverse bore 66 provided therefor in the body of L-shaped bracket 30, and stop 64 being carried in opposed relation to said end of armature 36 on the flanged portion 68 of a bracket 70 adjustably mounted at the rear of bracket 30 by means of set screws 72 passing through bracket 70 and threadedly engaging bracket 30, bracket 70 being transversely adjustable with respect to bracket 30 and the rear end of armature 36 by means of a transversely slotted opening 74 in bracket 70 for receiving each of said set screws 72. In assembled position stops 62 and 64 each lie on opposite sides of the free or rear end of armature 36 in spaced relation thereto. stop 64 being adjustably movable toward and from said armature by the adjustable movement of bracket 70 which carries it, and stop 62 being adjustably movable toward and from said armature by means of the inward or outward movement of a set screw 76 threadedly mounted in a threaded portion of the transverse bore 66 in L-shaped bracket 30 and in abutting engagement with said stop 62. The spacing of stops 62 and 64 from the free or rear end of armature 36 may be readily selected for permitting the vibratory power of said armature to be maximum.

For urging the armature 36 to move away from the magnet 32 about the axis of post 42 so as to assure vibratory operation of said armature about 75

said axis, the body of bracket 26 is internally provided with a transverse bore 78 which is at least partially threaded to receive a set screw 80 and a spring 82 in abutting engagement therewith, said set screw being adjustably operable for constraining said spring against said armature, and said spring being operable for holding said armature in normal position away from said magnet. The proper adjustment of the set screw 80, together with the proper adjustments of stops 62 and 64, tend not only to increase the vibratory power of the armature 36 by synchronizing the vibrations of said armature with the alternations of the current used but also to eliminate any noise other than a low and expected hum.

Supported in any suitable position within the casing 12, such as upon the rear leg of the magnet 32, is an insulating terminal post support 84 which is of fibrous or other non-conducting material and which is held in such supported position by means such as rivets or bolts 28 which interconnect the bracket 30 and rear leg of magnet 32. Upon support 84 are mounted in the usual manner the electrical terminal posts 86 to which the leads 88 coming through the inlet portion 14 of the casing 12 from the ordinary alternating current source are connected and from which posts 86 leads 90 are lead to be connected to the coil 34 of the vibratory mechanism of the razor 10. It is apparent that the armature 36, if the current used is the standard type characterized by 60 cycles/second, will pulsate 120 times per second.

The head of razor 10 includes a stationary, planar table member 100 which is substantially rectangular in cross section and rigidly secured to each flange 18 on the neck portion 16 of casing 12 by means of screws or rivets 102 so as to be positioned on said casing symmetrically with respect to the longitudinal axis of the razor and normal thereto. Table member 100 is formed centrally thereof with a laterally extending slot 104 for reception therethrough of the driving pin 58 and adapted for permitting lateral movement of said pin therein with respect thereto. A pair of laterally extending, substantially rectangular slots 106 is formed in the table member 100 one on each side of slot 104 and each being substantially equally spaced therefrom. Each end of table member 100 is formed with a downwardly extending, bearing-providing ear 108, a recess 109 (see Figs. 4 and 5) being formed between each ear and the adjacent, lower, forward portion of said table member, and the top of said table member is formed with a pair of coaxially aligned bearing portions 110, said portions being disposed on opposite sides of the longitudinal axis of the razor and substantially equally spaced therefrom. The utility of these various elements of which table member 100 is comprised will be subsequently discussed.

Secured to the driving pin 58 for movement therewith is a floating blade support, generally indicated at 112, adapted for riding back and forth on the forward planar surface of stationary table member 100. Support 112 comprises a main supporting body member 114 (see Figs. 6, 7 and 8) having a forward planar surface for supporting the razor blade (to be later discussed), a rear surface for riding on the forward planar surface of the stationary table member 100, a pair of rearwardly extending, rectangular-shaped bosses 116 spaced and shaped so as to fit snugly as to height within the spaced slots 106 in said table member and so as to fit

freely therewithin as to width to provide lateral play between each boss and its slot, and a rearwardly extending flange 118 at its lower end for preventing soap, shavings, etc., from passing between members 100 and 112 and which extends longitudinally of said body member 114 and slightly beyond each side end thereof to fit thereat into the recesses 109 formed between the ears 108 and the adjacent front portions of table member 100. It will be seen that, in addition to the support given to the floating blade support 112 by its rigid connection to the outer end of driving pin 58, which connection is more a driving connection than a means for supporting the support 112, the support 112 is more effectively and positively supported by the reception of the two ends of the flange 118 on the main body member 114 in the recesses 109 formed by and above the ears 108 on the stationary table member 100. In order to maintain the blade support 112 in supported relationship on and to the stationary table member 100 so as to be selectively removable therefrom, the bosses 116 are each bored to receive a rivet 120 which is substantially flush with the forward face of body member 114 and which extends through said body member to a position rearwardly of said boss, at which rearward extension said rivet is formed with a combination shoulder and head portion 122. Fitted about the shoulder portion of each rivet 120 between the head portion thereof and said boss there is provided a nut 124 of the wing type, each of said nuts 124 frictionally fitting onto the respective shoulder of said rivet for opposing the accidental turning of the former, and the wings of each of said nuts having a lateral expanse slightly less than the width of the slot 108 into which the nut is to be inserted and greater than the height of said slot so that, when the support 112 is to be supported on the table 100, each of the nuts 124 is turned to a position where its wing portions are horizontal so as to permit their reception into and by its respective slot 108, whereafter said nuts are each given a quarter-turn for permitting the wing portions thereof to lock said support 112 and table 100 together by the resulting cooperation between said wing portions and the portions of said table member adjacently above and below the slots 108 therein. The nuts 124 are so adapted that, when the wing portions thereof are locking the reciprocable blade support 112 and the stationary table support 100 therefor together, there will be little or no friction between said wing portions and said table support to oppose said reciprocation.

The floating blade support 112 also includes a pair of blade retaining members 126 which are preferably cast or otherwise made integral therewith. Members 126 are disposed at and carried by the opposite lower corners of the main body member 114 of support 112 and are flush with the plane of the rear surface of said body member so as not to interfere with the relative reciprocatory movement of members 100 and 114. Each of the members 126 extends upwardly from a position slightly below the lower surface of the flange 118 of member 114 to a position substantially mid-point of the latter, the outer side face of each member 126 being laterally spaced from the adjacent side face of member 114, and the forward face of each member 126 being forwardly spaced from the forward planar surface of member 114. Each member 126 comprises an

upper rectangular lug 128 which extends along the forward face of body member 114 in parallelism with the longitudinal centerline of said member 114, said lugs being in longitudinal alignment. Each member 126 is also provided at its lower end with another lug 130 which extends in parallelism with the lug 128 thereabove to a position just inwardly of the side face of member 114, lugs 130 being in longitudinal alignment. A recess or notch 132 is provided in each lug 130 at the portion thereof immediately adjacent the forward face of body member 114, said notches being in longitudinal alignment and of comparatively short length so that, when the reciprocating razor blade is supported on the floating blade support 112 in the manner to be described later, only the corners of said blade which are tightly supported in said notches will lack shaving utility. This is an advantage, however, because the face of the user will not be cut by these corners which are so confined within and covered by said notches. These notches also prevent forward displacement of the lower or cutting end of the blade from the face of member 114, the body itself of each of the members 126 preventing lateral displacement of the blade.

A razor blade 134, see Figs. 1, 2, 3 and 9, is provided for the razor 10 and is adapted for being supported on the reciprocable blade support 112 to reciprocate therewith. Blade 134 has a cutting edge 136 and a pair of longitudinally aligned, rectangular notches 138 one at either side edge of said blade and adapted for cooperation with the upper lugs 128 on members 126 when blade 134 is mounted on support 112, the fit between the notches 138 and lugs 128 being such as to prevent vertical or lateral play therebetween. The length of the cutting edge 136 of the blade 134, which is preferably the same as the length of the blade proper, is such as to permit the corners thereof to reside within the recesses or notches 132 in the lugs 130 of members 126 to be covered and held in place thereby against the forward face of member 114, the vertical distance between the notches 138 and cutting edge 136 being, of course, appropriate therefor.

For holding the upper end of the mounted blade 134 against the forward surface of member 114 and to prevent its unintentional forward displacement therefrom a spring clamp, generally indicated at 140, is pivotally mounted in the bearing portions 110 provided therefor in the stationary table member 100. Clamp 140 comprises a pair of spaced springs 142 each of which is hingedly mounted at one end to one of said bearing portions 110, and to the other ends of which springs is mounted a clamping member 144 which is movable with said springs toward and away from cooperative engagement with the forward face of the upper portion of the blade 134. The strength of the springs 142 is such that, when holding clamping member 144 against blade 134, the reciprocating movement of the latter is not materially obstructed. In Fig. 5 the spring clamp 140 is shown in inoperative position which enables ready replacement or removal of the blade from the razor.

For permitting the user to adjust the razor 10 to obtain either a close or a normal shave, a guide 146 is provided, said guide being disposed below and behind the cutting edge 136 of the blade 134 and extending the length thereof. Guide 146 is provided at either end with a pivot

pin 148, said pins being journaled in bearing portions 150 formed in the ears 108 on table member 100, and said pins being axially aligned though mounted eccentrically in said guide. In the position the guide 146 is shown in Figs. 2 and 10, a normal shave will result. In this position, a spring impressed detent 152 (see Figs. 2 and 10), mounted in each end of guide 146, is locked in a depression 154 formed in the ear 108 radially from the axis of pin 148. Another depression 156 (see Figs. 2, 3, 4 and 5) is formed in each ear 108 in spaced relation to depression 154 and at an equal radius from the axis of pin 148 so that, when guide 146 is rotated eccentrically about the axis of pins 148 away from the position shown in Fig. 2, detents 152 will be disengaged from depressions 154 and become engaged with depressions 156 to hold guide 146 in this new position.

In Figs. 12 and 13 a modified form of blade support is shown which may be employed in place of support 112 and clamp 140. It will be noted that this modified blade support, generally indicated at 212, comprises the flange 118, as does the support 112, but that it lacks the members 126, said members being replaced by a pair of spaced lugs 158 on the blade-carrying face of support 212. It is pointed out that support 212 is provided with the same means for securing it to the table member 100 as is support 112 and that the former is supported in the same manner as is the latter. It is to be noted also that the modified blade clamp, generally indicated at 248, is integral with the reciprocable support 212 rather than being pivoted to the stationary table member 100, the springs 142 being replaced by spaced arms 242 which are integral with support 212. Further, the clamp 144 has been replaced by a roll 244 which is eccentrically mounted between the arms 242 so as to have a plurality of positions of varying proximity to the forward surface of support 212, or the blade supported thereon. Still further, the blade 134 has been replaced by the modified blade 234, blade 234 lacking the slots 138 but being formed at each corner of its cutting edge with a shoulder 160 for cooperation with the respective lug 158 on support 212 to prevent downward and lateral displacement of said blade with respect to said support, it being noted that said blade, in assembly, not only cooperates at its lower edge with said lugs but that it also cooperates at its upper edge with the arms 242, the blade thereby being securely maintained on the support 212, especially when the roll 244 is in the position shown in Figs. 12 and 13.

In Fig. 11 there is shown a modified form of razor wherein the head and casing are made readily separable. In this form of construction table member 100 is formed on its rear surface with a centrally disposed cylindrical casing 101 made integral therewith. Casing 101 is operable for telescopically engaging the reduced end 162 of the rigid neck portion 216 of the razor casing 12, there being a pair of spaced pins 164 provided on the end 162 of portion 216 and which pins are cooperable in the ordinary manner with a pair of equally spaced bayonet slots 166 formed in the casing 101 for locking the members together or for permitting their ready separation.

Although the invention has been described with some detail it is not intended that such description is to be definitive of the limits of the inventive idea. The right is reserved to make such

changes in the specification and drawings as will come within the purview of the attached claims.

What I claim is:

- 5 1. In a razor having a cutting member and means for reciprocating same across the face of a user, a head for supporting the cutting member, said head comprising a pair of relatively movable plate members arranged in abutting engagement with each other and having parallel lower edges, one of said plate members being operable for supporting the other of said plate members and the latter being operable for removably supporting the cutting member, means 10 for removably connecting said plate members together without interfering with the relative movement therebetween, and a flange formed on and extending along said lower edge of one of said plate members and overlappingly engaging 15 said lower edge of the other of said plate members along the length thereof and in the vicinity of the cutting edge of the cutting member for preventing foreign matter from passing between said plate members and guiding said relative movement of the latter.
- 20 2. In a razor, a stationary plate, a movable plate in planar contact with the forward side of said first plate and having its lower edge rearwardly flanged and overlappingly engaging the 25 lower edge of said first plate along the length thereof, a blade carried on said second plate in spaced relation to said first plate and having a cutting edge adjacent said first mentioned lower edge and in parallelism therewith, means 30 operable with the outer face of said blade for holding the latter against said second plate, and means operable for unitarily reciprocating said second plate, said blade and said first means relatively to said first plate in the direction of 35 the lengths of said edges.
- 40 3. In a razor, a stationary plate, a movable plate in planar contact with the forward side of said first plate and having its lower edge rearwardly flanged and overlappingly engaging the 45 lower edge of said first plate along the length thereof, a blade having a cutting edge and arranged forwardly on said second plate with said cutting edge adjacent and in parallelism with said first mentioned lower edges, and means carried forwardly on said second plate for receiving the two end portions of said cutting edge and leaving exposed the portion of said cutting edge therebetween.
- 55 4. In a razor having a casing and an oscillatably movable actuator supported thereby, a supporting structure for a blade and comprising, an elongated plate stationarily secured to the casing and having a central aperture through which the actuator projects and to which the latter is 60 freely and relatively movable, a pair of other apertures formed in said plate in lateral spaced relation to and on opposite sides of said central aperture, a second elongated plate fixedly connected to the actuator for movement therewith and disposed forwardly of said first plate, a pair of bosses formed on said second plate in spaced relation to each other similarly as said pair of apertures and extending through the latter, fastening means carried by each of said bosses and cooperable with portions of said first plate externally of said pair of apertures for removably interconnecting said two plates and permitting lengthwise movement of said second plate relatively to said first plate, means formed at oppo-

site ends of said second plate and extending forwardly therefrom for being received in end openings provided therefor in the blade to oppose vertical movement of the latter relatively to said second plate, other means formed at said opposite ends of said second plate for being abutted by the blade ends to oppose lengthwise movement of the blade relatively to said second plate, and means carried by and movable with the upper end of said second plate for removably interconnecting the latter and the upper end of the blade to oppose movement of said last mentioned upper end away from said second plate.

5. In a razor having a casing and an oscillatably movable actuator supported thereby, a supporting structure for a blade and comprising, an elongated plate stationarily secured to the casing and having a central aperture through which the actuator projects and to which the latter is freely and relatively movable, a pair of 20 other apertures formed in said plate in lateral spaced relation to and on opposite sides of said central aperture and each having a predetermined length, a second elongated plate fixedly connected to the actuator for movement therewith and disposed forwardly of said first plate, a pair of bosses having lengths in cross section substantially less than said lengths of said pair of apertures and formed on said second plate with a spacing between the centers thereof equal 30 substantially to the spacing between the centers of said pair of apertures and extending through the latter, fastening means carried by each of said bosses and cooperable with portions of said first plate externally of said pair of apertures for removably interconnecting said two plates and permitting lengthwise movement of said second plate relatively to said first plate to the extent of the difference between said lengths of said bosses and said pair of apertures, means formed at opposite ends of said second plate and extending forwardly therefrom for being received in end openings provided therefor in the blade to oppose vertical movement of the latter relatively to said second plate, other means formed at said opposite ends of said second plate for being abutted by the blade ends to oppose lengthwise movement of the blade relatively to said second plate, and means carried by and movable with the upper end of said second plate for removably interconnecting the latter and the upper end of the blade to oppose movement of said last mentioned upper end away from said second plate.

6. In a razor having a casing and an oscillatably movable actuator supported thereby, a supporting structure for a blade and comprising, an elongated plate stationarily secured to the casing and having a central aperture through which the actuator projects and to which the latter is freely and relatively movable, a pair of 40 other apertures formed in said plate in lateral spaced relation to and on opposite sides of said central aperture, a pair of bearing-forming mem-

bers carried by the opposite lower corners of said plate and extending therebelow to provide spaces between the tops of said members and the lower edge of said plate, a second elongated plate fixedly connected to the actuator for movement therewith and disposed forwardly of said first plate, a flange formed along the lower edge of said second plate and operable for being received in said spaces to be supported by said members, a pair of bosses formed on said second plate in spaced relation to each other similarly as said pair of apertures and extending through the latter, fastening means carried by each of said bosses and cooperable with portions of said first plate externally of said pair of apertures for removably interconnecting said two plates and permitting lengthwise movement of said second plate relatively to said first plate, said second plate removably carrying a blade on the forward side thereof for movement therewith, and guide means extending between and supported by said members for guiding the blade during the shaving operation.

7. In a razor having a casing and an oscillatably movable actuator supported thereby, a supporting structure for a blade and comprising, an elongated plate stationarily secured to the casing and having a central aperture through which the actuator projects and to which the latter is freely and relatively movable, a pair of other apertures formed in said plate in lateral spaced relation to and on opposite sides of said central aperture and each having a predetermined length, a pair of bearing-forming members carried by the opposite lower corners of said plate and extending therebelow to provide spaces between the tops of said members and the lower edge of said plate, a second elongated plate fixedly connected to the actuator for movement therewith and disposed forwardly of said first plate, a flange formed along the lower edge of said second plate and operable for being received in said spaces to be supported by said members, a pair of bosses having lengths in cross section substantially less than said lengths of said pair of apertures and formed on said second plate with a spacing between the centers thereof equal substantially to the spacing between the centers of said pair of apertures and extending through the latter, fastening means carried by each of said bosses and cooperable with portions of said first plate externally of said pair of apertures for removably interconnecting said two plates and permitting lengthwise movement of said second plate relatively to said first plate to the extent of the difference between said lengths of said bosses and said pair of apertures, said second plate removably carrying a blade on the forward side thereof for movement therewith, and guide means extending between and supported by said members for guiding the blade during the shaving operation.

ALFRED J. STECKER.
